UNITED STATES PATENT OFFICE.

BERNHARD EDWARDS, OF SANFORD, FLORIDA.

SIDE CLOSURE FOR MOTOR VEHICLES.

Application filed January 16, 1924. Serial No. 686,652.

To all whom it may concern:

Be it known that I, BERNHARD EDWARDS, citizen of the United States, residing at Sanford, in the county of Seminole and State of Florida, have invented certain new and useful Improvements in Side Closures for Motor Vehicles, of which the following is a specification.

This invention relates to an improved 10 side closure for motor vehicles and seeks, among other objects, to provide a closure embodying a pair of curtains which may be conveniently mounted upon the top frame of the vehicle in a position out of the way 15 and which may be easily drawn down and secured for excluding the weather.

The invention seeks, as a further object, to provide a closure comprising a front curtain which will also embody a front flap 20 to be secured adjacent the windshield of the vehicle so that when all of the curtains of the vehicle equipped with the invention are drawn down, the vehicle will be snugly enclosed.

25 And the invention seeks, as a still further object, to provide a closure which will be of simple construction, which will be well adapted for use upon different makes of vehicles, and which, when applied, will not prove unsightly.

Other and incidental objects will appear hereinafter.

In the drawings:

35 Figure 1 is an elevation looking at the right hand side of a conventional motor vehicle and showing my improved closure applied.

40 Figure 2 is an enlarged transverse sectional view on the line 2—2 of Figure 1, looking in the direction of the arrows.

Figure 3 is an enlarged transverse sectional view on the line 3—3 of Figure 1, looking in the direction of the arrows,

45 Figure 4 is a detail elevation of the front curtain employed and showing the curtain unrolled, the casing for the curtain being illustrated in section,

50 Figure 5 is a detail sectional view on the line 5—5 of Figure 1, looking in the direction of the arrows,

Figure 6 is a detail sectional view on the line 6—6 of Figure 1, looking in the direction of the arrows,

55 Figure 7 is a detail sectional view on the line 7—7 of Figure 3, looking in the direction of the arrows, and

Figure 8 is a detail sectional view on the line 8—8 of Figure 2, looking in the direction of the arrows.

In accordance with the present invention, 60 the improved side closure preferably comprises a front curtain and a complementary back curtain and, for convenience, I have, in the drawings, shown the closure in conjunction with a conventional motor vehicle. 65 The back bow of the vehicle top frame is indicated at 10. Connected with this bow are side bars 11 and pivoted upon said side bars is a front bow 12.

The front curtain will be first taken up 70 in detail. A preferably cylindrical sheet metal casing 13 is employed. As brought out in Figure 2, this casing is open at its lower side and closing the casing at its forward end is a removable end plate 14. As 75 best shown in Figure 4 of the drawings, this end plate is provided with a flange 15 snugly fitting in the casing and extending through the casing and through said flange are bolts 16 securing the plate in position. 80 Formed in the plate is, as clearly shown in Figure 2, a vertical slot 17. At its rear end the casing is equipped with a permanent end plate 18 while, as best brought out in Figure 7, the rear end portion of the casing 85 is provided at one side thereof with a notch 19 extending longitudinally of the casing from its adjacent extremity. Appropriately secured to the casing near its forward end is a bracket 20 which is extended laterally 90 from the casing to define a loop 21 shaped, as particularly shown in Figure 2, to snugly embrace the adjacent side member of the front bow 12 and extending through the free end of the loop and through the bracket 95 is a bolt 22 clamping the loop in firm engagement with the bow. Appropriately secured to the casing near its rear end is a bracket 23 which is extended laterally from the casing to define a substantially U-shaped 100 hook 24 snugly accommodating the adjacent side bar 11 of the top frame of the vehicle and extending through the bracket and through the free end of said hook is a bolt 25 rigidly clamping the bracket in engagement with the bar. Thus, the brackets 20 and 23 will serve to firmly support the casing 13 to extend horizontally within the vehicle top at the adjacent side of the vehicle and, as will be perceived, the casing 105 may be readily applied.

Mounted within the casing 13 is a spring

roller 26, the trunnions of which are accommodated through the end plates 14 and 18 of the casing and secured to said roller is a curtain 27 which, as brought out in Figure 1, is provided with appropriate windows 28. At its forward end, the curtain is provided with a front flap 29 extending throughout the major portion of the length of the curtain and this flap is also preferably 5 equipped with an appropriate window 30. Mounted upon the curtain in spaced relation to the forward edge thereof is, as shown in Figure 4, the stud 31 of an appropriate snap fastener and mounted upon the upper 10 outer corner of the flap is a socket 32 to accommodate said stud. As shown, the stud 31 is so located that when the flap 29 is folded back over the curtain at its inner side, the socket 32 may be engaged with the stud 31 15 for securing the flap in folded position. Furthermore, as also brought out in Figure 4, the roller 26 is formed with a reduced forward end portion 33 to accommodate the double thickness presented by the curtain 20 and flap so that the curtain with the folded flap will wind evenly upon the roller. Secured by a hem at the lower edge of the curtain is, as shown in Figure 5, a flat resilient bottom strip 34 extending from end to end 25 of the curtain but terminating at the junction of the flap 29 with the curtain. This bottom strip is bowed longitudinally, being arranged with its concave face presented inwardly, and bolted or otherwise secured to 30 the strip at a point medially thereof is, as shown in detail in Figure 6, a hand hook 35. Engaged through the curtain and through the upper end of said hook is the socket 36 35 of an appropriate snap fastener and secured 40 by said socket is a thumb tab 37.

The hook 35 is provided for raising or lowering the curtain from the exterior of the vehicle while the thumb tab 37 is provided for raising or lowering the curtain from 45 the interior of the vehicle and, as will now be seen, the curtain may be drawn down to overlap the vehicle body at its adjacent side. The vehicle body is, as shown in Figure 6, provided with a stud 38 to cooperate with 50 the socket 36 so that after the curtain has been drawn down it may be readily secured by engaging the socket over said stud. Since the bottom strip 34 is bowed longitudinally, said strip will contact at its ends with the 55 side of the vehicle body and when the socket 36 is engaged with the stud 38, said strip will be flexed longitudinally and held under tension to yieldably bear against the side of the vehicle body and prevent flapping 60 of the curtain. However, before the bottom strip is secure, the flap 29 is, after the curtain has been drawn down, released at the stud and socket 31 and 32 and extended forwardly from the curtain about the adjacent end of the vehicle windshield, and

mounted upon the front bow 12 of the frame of the vehicle top near the adjacent upper corner of the windshield is, as shown in detail in Figure 8, a stud 39 projecting rearwardly from the bow. As illustrated, the upper outer corner of the flap is folded outwardly upon itself to present the socket 32 to said stud when the socket is engaged over the stud for securing the flap at its upper end. Mounted upon the flap near its lower outer corner is an appropriate eyelet 40 accommodating a suitably located turnbutton 41 upon the vehicle for securing the flap at its lower end. Thus, the flap will be securely held to overlap the adjacent end of the windshield and attention is now directed to the fact that when the curtain 27 is fastened down, the upper margin of the flap is accommodated through the slot 17 in the end plate 14 of the casing 13 so that the flap 45 may extend at its upper margin smoothly from the curtain and form a neat junction with the casing.

Coming now more particularly to the rear curtain, I employ a cylindrical sheet metal casing 42 similar to the casing 13 of the front curtain. The casing 42 is open at its lower side and is equipped at its ends with end plates 43, one of which is like the end plate 14 and is removable. Appropriately secured to the casing near its forward end is a bracket 44 extended downwardly at one side of the casing, as particularly shown in Figure 3, to form a hook 45 accommodating the adjacent side bar 11 of the top frame of the vehicle, and inserted through the free end of the hook and through the bracket is a bolt 46 clamping the bracket in firm engagement with the side bar. In this connection, it is to be observed that the bracket 44 is of a length to support the forward end of the casing 42 above the rear end of the casing 13 of the front curtain and the casing 42 is arranged to overlap or overhang the casing 13 a distance equal to the length of the notch 19 of the latter casing. Appropriately secured to the casing 42 at its rear end is, as shown in Figure 1, a bracket 47 extended downwardly at the adjacent side of the casing and provided with openings to receive wood screws securing the bracket to the rear bow 10 of the top frame of the vehicle. The brackets 44 and 47 will thus serve to rigidly sustain the casing 42 to extend horizontally within the vehicle top substantially in a plane with but slightly above the casing 13 and journaled within the casing 42 is an appropriate shade roller 48, the trunnions of which are accommodated in suitable openings in the end plates 43. Secured to the roller 48 is a curtain 49 which, as brought out in Figure 1, is provided with appropriate windows 50 while the curtain is formed with an oblique rear edge to conform to the inclination of the adjacent side of the

rear bow 10 of the top frame when the curtain is drawn down. Mounted upon the curtain near the rear edge thereof are eyelets 51 to accommodate the usual studs upon the 5 said side of the rear bow for securing the curtain to said bow and enclosed within a hem at the lower margin of the curtain is a longitudinally bowed flat resilient bottom strip 52 similar to the strip 34 of the front 10 curtain. Secured to said strip is a hand hook 53 similar to the hook 35 and associated with said hook is a socket 54 like the socket 36 as well as a thumb tab like the thumb tab 37. At its adjacent side, the vehicle body is provided with a stud like the stud 38 to receive 15 the socket 54 so that the curtain may be readily fastened down when the bottom strip 52 of the curtain will, like the strip 34, be tensioned against the side of the vehicle for holding the curtain against flapping. Since 20 the casings 13 and 42 are overlapped at their meeting ends the curtains 27 and 49 are, when drawn down, correspondingly overlapped and for this reason, the casing 25 13 of the front curtain is provided with the notch 19 to accommodate, as shown in Figure 3, the forward margin of the rear curtain 49. A close joint will, therefore be formed between the overlapped portions of the curtains 27 and 49 so that the use of fastening 30 devices between the curtains will be unnecessary. However, the front curtain 27 is, of course, arranged at the outside of the rear curtain so that when the vehicle is moving 35 forwardly, currents of air will not enter between the curtains. In the present instance, I have shown a right hand side closure.

However, as will be at once understood, a left hand side closure will, of course, be provided and mounted in like manner. 40

Having thus described the invention, what I claim as new is:

1. In a side closure for motor vehicles, a casing having end plates, a roller mounted upon said end plates to extend within the 45 casing, and a curtain carried by the roller to be withdrawn from the casing and provided with a front flap adapted to be extended forwardly from the curtain, one end plate of the casing being provided with a slot 50 to accommodate the flap when extended.

2. The combination with a motor vehicle having a top embodying a frame, of front and rear casings secured to the frame to extend longitudinally of the top at one side 55 thereof and overlapping at their confronting ends, rollers mounted in the casings, and curtains carried by said rollers and adapted to be drawn down closing the top at its adjacent side and overlapping at their confronting margins, one of the casings being notched at one side thereof to accommodate the overlapping margin of the curtain of the other casing. 60

3. In a side closure for motor vehicles, a curtain roller, and a curtain carried by the roller and provided with a flap, the flap being adapted to be folded back to overlie the curtain and the roller being provided with a reduced portion to accommodate the 65 double thickness presented by the flap and curtain. 70

In testimony whereof I affix my signature.
BERNHARD EDWARDS. [L. S.]
